CLAIM

The ornamental design for a downspout extension, as shown and described.

DESCRIPTION

FIG. 1 is a front, top perspective view of a downspout extension, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded view thereof;

FIG. 10 is a rear, bottom perspective view thereof;

FIG. 11 is front elevation view thereof;

FIG. 12 is a rear elevation view thereof;

FIG. 13 is a left side elevation view thereof;

FIG. 14 is a right side elevation view thereof;

FIG. 15 is another perspective view of the downspout extension, shown in an alternative position;

FIG. 16 is another perspective view of the downspout extension, shown in condition of use; and,

FIG. 17 is an enlarged view of detail "17" identified in FIG. 9.

The dashed lines in the figures illustrate portions of the downspout extension that form no part of the claimed design. The dash dot dash lines in FIGS. 9 and 17 are for the purpose of illustrating the enlarged view indicators and form no part of the claimed design.

1 Claim, 17 Drawing Sheets
